CONVERTIBLE BASKET-TABLE

Application filed December 28, 1928. Serial No. 328,996.

This invention relates to a device adapted to be used by those engaged in selling merchandise directly to householders, and has for one of its objects to provide a novel device of this character which shall be adapted to be used as a basket in which the merchandise may be conveniently carried from house to house and which shall be adapted to be used as a table on which the merchandise 10 may be attractively displayed to a householder.

The invention has a further object to provide a device of the character stated which shall be adapted to be easily and quickly 25 converted from a basket into a table and from a table into a basket.

The invention has for a further object to provide a device of the character stated which shall embody members connected in a manner to permit them to be arranged in basket or table top forming relation and legs connected to one of said members for movement into extended or folded relation with respect thereto.

25 The invention has for a further object to provide a device of the character stated which shall embody means adapted to hold the legs against accidental movement when extended, and means adapted to hold the 30 legs against accidental movement when folded.

The invention has for a further object to provide a device of the character stated which shall be equipped with a handle and with 35 means adapted to hold the members against accidental movement from basket forming position, said means embodying elements carried by the handle and adapted to automatically engage certain of the members on their movement into basket forming position.

The invention has for a still further object to provide a device of the character stated which shall be adapted to be manufactured 45 and sold at a comparatively low cost and which shall be light in weight and strong and durable.

The invention is hereinafter more fully described and claimed, and illustrated in the 50 accompanying drawings, wherein:

Figure 1 is a view in side elevation of the device in basket form;

Figure 2 is a bottom plan view of the device in basket form;

Figure 3 is a top plan view of the device 55 in basket form;

Figure 4 is a sectional view taken on the vertical plane indicated by the line 4—4 of Figure 3;

Figure 5 is a sectional view taken on the 60 vertical plane indicated by the line 5—5 of Figure 3;

Figure 6 is a view in end elevation of the device with the members 4 in basket forming relation and with the legs in extended position;

Figure 7 is a view in side elevation of the device as shown in Figure 6;

Figure 8 is a view in side elevation of the device in table form with the lower portions 70 of the legs and the upper portion of the handle broken away;

Figure 9 is a top plan view of the device in table form;

Figure 10 is a view in end elevation of the 75 device in table form;

Figure 11 is a detail elevational view illustrating the manner in which the side members are retained in basket forming position;

Figure 12 is a sectional view taken on the vertical plane indicated by the line 12—12 of Figure 11, and

Figure 13 is a detail sectional view taken on the vertical plane indicated by the line 85 13—13 of Figure 12.

The device comprises a central member 1, side members 2 and end members 3. The side members 2 and the end members 3 are connected to the central member 1 by hinges 4 and 5, respectively, so as to permit them to be arranged either at right angles to the central member to provide a basket or in the plane of the central member to provide a table top. The members 1, 2 and 3 may be made from wood, metal or any other suitable material. When the members 2 and 3 are in basket forming position, the side members 2 contact with the end edges of the end members 3, and when these members are in table 90 95 100

top forming position, their hinged edges contact with the edges of the central member 1. The side members 2 are provided with angle irons 6 and blocks 7 which, when these 5 and the end members 2 are in basket forming position, contact with the opposite faces of the end members to hold said members against any accidental inward or outward movement. When the side members 2 and 10 end members 3 are in basket forming position, the side members rest against the sides of a handle 8 and are engaged by the bolts 9 of latches 10, the sides of the handle being arranged inwardly and the bolts 9 being arranged outwardly of the side members. The 15 bolts 9 which are vertically arranged and slidably mounted in casings 11, are yieldingly held in projected position by springs 12, so as to permit them to automatically engage the side members 2 when the latter are 20 swung into basket forming position against the sides of the handle 8. Headed pins 12 working in slots 14 in the casings 11, serve to limit the movement of the bolts 9 by the 25 springs 12 and provide means through the medium of which the bolts may be retracted when it is desired to swing the side members 2 and end members 3 into table top forming 30 position.

30 The handle 8 is arranged at the transverse center of the device, and extends for a considerable distance above the side members 2 and end members 3 when said members are in basket forming position. It is secured to 35 the central member 1, and comprises a pair of rods 15 of substantially inverted U-form in elevation and arranged in relatively spaced relation. The lower ends of the rods 15 extends downwardly through openings 16 in the central member 1, and are bent into contact with the lower side of said member. Cleats 17 provided with openings for the 40 reception of the angular ends of the rods 15, and secured to the under side of the central member 1 by elements 18, serve to firmly secure the rods to said member. The sides of the rods 15 are offset laterally at points immediately above the side members 2 so as to 45 provide the handle 8 with a comparatively large upper or looped portion. The upper or looped portions of the rods 15 are held 50 against any relative movement by a metal strap 19 of inverted U-form in elevation and arranged within said portion of the rods 55 with its ends resting upon the shoulders 20 provided by offsetting the rods. The side edges of the strap 19 are rolled, as at 21, about the upper or looped portions of the rods 15. In addition to strengthening and 60 adding rigidity to the handle 8, the strap 19 provides a smooth grip which will not tire the hand. The latch casings 11 are welded or secured in any other suitable manner to the inner sides of the ends of the strap 19, 65 and the bolts 9 pass downwardly through the

shoulders 20 into contact with the outer faces of the side members 2.

The legs 22 and 23 are arranged in pairs, and are connected to the under side of the central member 1 for movement into extended or folded relation with respect thereto. When the legs 22 and 23 are in extended position, the central member 1 rests upon their upper ends and when they are in folded position, they occupy a common plane. The 70 legs 22 and 23 are connected to the central member 1 by hinges 24. The legs 22 are connected together by crossed braces 25, and the legs 23 are connected together by a transverse brace 26. The brace 26 is provided with an offset portion 27 which constitutes a spring latch adapted to engage a keeper plate 28 on one of the legs 22 when these legs and the legs 23 are in folded position, the latch serving to hold the legs against accidental movement from such position. A 75 rod 29 extending across and secured to the upper ends of each pair of the legs 22 and 23, end springs 30 secured to the central member 1 and to the arms or cranks 31 of 80 said rods, provide means for holding the legs in extended position and for moving the legs into such position when they are released by disengaging the latch 27 from the keeper plate 28. 85

In practice, the salesman carries his merchandise in the basket provided by arranging and securing the side members 2 and end members 3 in upright position with respect to the central member 1, the legs 22 and 23 being in folded position against the under side of the basket, in which position they are secured by the latch 27. When he wishes to display the merchandise to a prospective purchaser, he frees the legs 22 and 23 for movement into their extended position by the springs 30. After the legs 22 and 23 have reached their extended position, in which position they will be held by the 90 springs 30, he rests the device upon the floor, and thereafter frees the side members 2 to fall into alignment with the central member 1, with the result that a table having a broad flat top is provided. He now spreads the merchandise over the table top in order to display them to the best advantage to the prospective purchaser. When he wishes to visit another prospective purchaser, he arranges the merchandise on the central member 1, then swings the end members 3 into 95 basket forming position, and thereafter swings the side members 2 into basket forming position, the side members securing the end members in such position and the side members being automatically secured in such 100 position by the latches 10. After the basket has been formed, the legs 22 and 23 are swung into folded position against the under side of the basket, in which position they are automatically secured by the latch 27. 105

From the foregoing description, taken in connection with the accompanying drawings, it will be seen that a salesman equipped with this device has at hand a table on which he may display his merchandise to the best advantage, and that the device, due to the fact that it provides a table for the merchandise, obviates the loss of time incident to and the bad impression created by a salesman who is equipped with only a basket or tray which in the absence of a better support is usually placed on the floor and who accordingly must constantly be bending over the basket in order to select merchandise for display to a prospective purchaser.

While we have described the principle of the invention and the device which we now consider the best embodiment thereof, we wish it to be understood that the device shown is merely illustrative and that such changes may be made therein when desired as are within the scope of the invention as claimed.

What we claim is:

- 25 1. A device of the character set forth, comprising a central member, other members connected to the central member for arrangement into basket or table top forming position with respect thereto, means carried by certain of said other members and engaging the remaining of said other members to hold said remaining members in basket forming position, a handle secured to the central member, releasable means carried by said handle and engaging said certain members intermediate their ends to hold them in basket forming position, and means for supporting the members when in table top formation.
- 40 2. A device of the character set forth, comprising a central member, other members connected to the central member for arrangement into basket or table top forming position with respect thereto, means carried by certain of said other members and engaging the remaining of said other members to hold said remaining members in basket forming position, a handle secured to the central member, and means carried by said handle and engaging said certain members to hold them in basket forming position.

- 45 3. A device of the character set forth, comprising a central member, other members connected to the central member for arrangement into basket or table top forming position with respect thereto, means carried by certain of said other members for engagement with the remaining of said other members to hold the remaining members in basket forming position, a handle secured to the central member, and spring pressed bolts carried by the handle and adapted to engage said first members to hold them in basket forming position.
- 55 4. A device of the character set forth, com-

prising a central member, other members connected to the central member for arrangement into basket or table top forming position with respect thereto, a handle secured to the central member and embodying sides, certain of said other members resting against the sides of the handle when in basket forming position, latches engaging said members to hold them in said position, and means carried by said members and engaging the remaining other members to hold them in basket forming position.

5. A device of the character set forth, comprising a central member, other members connected to the central member for arrangement into basket or table top forming position with respect thereto, U-shaped wires having their ends passing through the central member, means securing the ends of the wires to the lower side of the central member, a strap embracing the upper portions of the wires, certain of said members contacting with the sides of the wires when in basket forming position, latches carried by the strap and engaging said members to hold them in said position, and means carried by said members and engaging the remaining other members to hold them in basket forming position.

6. A device of the character set forth, comprising a central member, other members connected to the central member for arrangement into basket or table top forming position with respect thereto, means releasably holding said other members in basket forming position, pairs of legs, means connecting the legs to the central member for movement into folded or extended position with respect thereto, means releasably holding the legs in folded position, a cross bar secured to one pair of legs and having a catch engaging one of the other pair of legs to hold the legs in folded position, and means for releasably holding the legs in extended position.

7. A device of the character set forth, comprising a central member, other members connected to the central member for arrangement into basket or table top forming position with respect thereto, means releasably holding said other members in basket forming position, pairs of legs, means connecting the legs to the central member for movement into folded or extended position with respect thereto, means releasably holding the legs in folded position, rods carried by the legs and provided with cranks, and springs secured to the central member and to the cranks.

In testimony whereof we affix our signatures.

ORIN A. JOHNSTON.
CLARENCE F. JOHNSTON.
